G. W. TONEY

TIMEPIECE WITH HAND DRIVING EXTENSION

Filed Jan. 3, 1921

A technical line drawing of a mechanical assembly. On the left, a vertical column is labeled with numbers 26, 22, 21, 27, 1, 25, 28, 16, 15, 14, 83, 10, 19, 18, 171, 12, 13, 9, 10, 16, and 18. The assembly includes a base, a central vertical rod, and various structural elements. A handwritten label 'Fig.' is located in the lower right corner of the drawing.

UNITED STATES PATENT OFFICE.

GEORGE W. TONEY, OF WALTHAM, MASSACHUSETTS, ASSIGNOR, BY MESNE ASSIGNMENTS, TO OLD COLONY TRUST COMPANY, TRUSTEE, A CORPORATION OF MASSACHUSETTS.

TIMEPIECE WITH HAND-DRIVING EXTENSION.

Application filed January 3, 1921. Serial No. 434,748.

The ultimate specific object of the present invention is to combine a time piece with a speedometer-odometer instrument, which has not sufficient room in its own casing to contain a time piece, in a manner such that the hands of the time piece are exposed to view within the circumference of the dial or face plate with which the instrument is provided. Speedometer-odometer instruments have been produced in combination with clock movements for showing by means of a single combined instrument the current time as well as the speed of the vehicle to which the instrument is applied and the distance traveled by the vehicle; but such combined instruments are especially designed as to the size and shape of their cases to provide interior space for the accommodation of the time piece movement. Other speedometer-odometer instruments have been put out in large numbers without a clock attachment, and in instruments of that type the mechanism and case, designed primarily for compactness and the convenient exhibition of the speed and distance indications, has not any large enough clear space in its interior for accommodating a clock movement. The ordinary instrument of this type, however, has enough space upon its dial or face for mounting or exhibiting a clock dial and to permit rotation of time indicating hands thereover.

Commonly such instruments exhibit the speed indications in the upper part of the dial and show distance indications, respectively of the total distance traveled and of the distance of single trips, in positions side by side slightly below the horizontal diameter of the dial. Space enough is available between such distance indications and the lower part of the case for exhibition of a clock dial and hands. It is with this type of instrument that the particular aspect of my invention above stated is concerned; and that phase of the invention consists in the provision of means for mounting a time piece outside of the casing of the speedometer instrument and means for driving the hands in a visible location over the dial thereof from the time piece so mounted.

The foregoing statement, however, is not to be construed as defining the limits within which I desire protection; for the principle embodied in the extended driving

means for the hands of a time piece is applicable to other combinations for other specific uses and I claim protection for the same in the broadest scope permitted by the prior art, as well as for the specific combination above referred to.

For a full understanding of the nature of the invention and of its application to its preferred special use, I have shown in the drawings accompanying this specification, and will presently describe in detail, a speedometer-odometer instrument having a clock movement mounted upon the back of its case and having hands visible in front of its dial which are driven through extended driving members.

In said drawings, Figure 1 is a face view of an instrument equipped with this invention represented as though placed in an upright position with its face in a vertical plane. Figure 2 represents the instrument as seen from beneath the position represented in Figure 1, and shows the case as being partly broken away to reveal the hand-driving means of the time piece. Figure 3 is a longitudinal sectional view on an enlarged scale of the extension hand driving means in complete detail. Figure 4 is a fragmentary sectional view showing those ends of the extension sleeves which, in use, are connected to the movement of the time piece. Figure 5 shows a cross section taken on line 5-5 of Figure 3 viewed in the direction of the arrows on that figure.

Like reference characters designate the same parts in all the figures.

The instrument here shown has a cylindrical case 1, the dimensions of which are such as to contain conveniently the speed indicator, the distance counters, and the mechanisms which operate them, such indicator and counters being arranged in a manner common at the present day in instruments of this nature. In the front of the casing is mounted a dial 2 having sight-openings 3, 4 and 5. A speed indicator 6 is visible through the opening 3; counters 7 for showing the total distance traveled by the vehicle to which the instrument is applied are visible through the opening 4, and counters 8 showing the distance traveled in single trips are seen through the opening 5. The dial is covered by a crystal 9 mounted upon the case by a bezel 10.

This illustration shows a common type of instrument and is given to illustrate the nature and principles of the invention, but without intent to indicate limitation of the invention to any specific style or make of speedometer instrument. The facts particularly intended to be shown here are that enough clear space exists on the dial between the distance indicators and the lower limb of the bezel to accommodate visibly a clock dial and hands, but that the size and shape of the case do not provide large enough interior space to contain a clock movement.

The time dial is shown in Figure 1 at 11 and the hands at 12 and 13, 12 being the minute hand and 13 the hour hand. Said time dial may be made, or constructed or applied in any desired way on the dial proper of the instrument, whether printed, drawn or engraved directly on said dial, or made as a separate piece applied thereto, or otherwise.

The clock movement is contained in its own case 14 which is mounted on the back of the speedometer case in the position which brings the center staff of the clock movement in line with the center of the time dial 11. This placement of the clock case may bring its circumference outside of the circumference of the speedometer case, and it is so shown in Figure 1; but that is no detriment to the combined instrument because in the usual mode of mounting said instruments they are set and fitted in apertures in the dashboards or instrument boards of automobiles, where only their faces are visible, wherefore the projecting part of the clock case is concealed by the instrument board.

It is to be understood, also, that the particular placement of the time dial and clock movement here shown is not obligatory, but that the time dial may be placed in any other part of any specific style of speedometer dial where there is room for it and where also the mechanism of the speedometer instrument leaves an open way for the extension of a driving shaft from the clock movement at the rear to the hands arranged over the time dial.

The clock case may be secured to the speedometer case in any suitable way by any suitable means, either permanently or detachably. In the present showing the clock case is made in one piece with a back plate secured detachably to the rear of the speedometer-odometer case and provided with lugs 16 by which the entire combined instrument may be secured upon the dash or other instrument board of an automobile. A detachable rear cover 17 closes the clock case and gives access to the movement contained therein.

The clock movement may be of any standard type or other design; all that is material

to the present disclosure being that it has a cannon pinion 17' or equivalent means for delivering motion from its center staff to the minute hand, with provision for shifting of such hand in setting, and a gear train 70 ending in an hour wheel 18 for delivering motion to the hour hand. An extension sleeve or tubular shaft 19 surrounds at its rear end the hub 20 of the hour wheel and extends toward the dial 2, carrying at its 75 forward end a bushing 21 which rotates in the dial and has a reduced extension 22 for mounting the hour hand.

An inner extension sleeve or tubular shaft 23 is applied at its rear end to the extended hub 24 of the cannon pinion, and at its forward end it is connected to a staff 25 which has a bearing in the reduced end 22 of the bushing 21, extends beyond the same, and is reduced in diameter at its forward end 26 85 to receive and hold the minute hand. The bushing 21 and staff 25 are preferably formed with shoulders 27 and 28, respectively, to limit their penetration into the extension sleeves, and are secured firmly to 90 said sleeves in order to make driving units therewith, preferably by solder, or they may be so secured by friction, or in any other convenient way.

Detachable driving engagement between the sleeve 19 and the hour wheel is effected by forming a transverse notch 29 in the hub of said wheel and a complementary indentation or offset 30 in the wall of the tube. The end of the sleeve is split or slotted as shown at 31 in Figure 4, so that it may be sprung over the hub and cause the offset 30 to snap into the notch 29 when brought into registration therewith. Preferably this offset is located at a distance from the end 100 of the sleeve equal to the distance of the notch from the face of the hour wheel, whereby the end of the sleeve then abuts against the hour wheel. Preferably, also, the complementary notch and offset extend in 105 a direction transverse to the axis of the sleeve and are run in straight lines, or at least, in lines otherwise than concentric with such axis, whereby their engaging surfaces cross the path or paths in which such surfaces rotate. Thus the notch and indentation are at the same time means for resisting withdrawal of the sleeve from the hour wheel and means for transmitting rotation from the latter to the former. Other forms 110 of means for the same purpose may be provided, but the particular one here shown is preferred on account of its simplicity and efficiency. The notch and offset are here shown as being V-shaped, but that specific 115 form may be modified.

A similar means for effecting connection and driving engagement between the inner or minute hand sleeve and the cannon pinion are provided, consisting of a notch 32 in 120

the side of the cannon pinion hub and an offset 33 in the contiguous part of the sleeve, said sleeve being slotted at its rear end, as indicated at 34 in Figure 4.

5 When removal of the clock movement from the speedometer is required for repairs upon either the clock or the speedometer, these extension sleeves may be readily disconnected from the clock movement, and 10 as easily replaced after the repairs have been made; and when assembled in the relation shown the interlock of the sleeves affords ample resistance to their independent rotation relatively to the hour wheel and cannon pinion, respectively, to drive the hands in exact synchronism with the clock movement.

In the foregoing description the reference 20 to positions of the parts shown, as being respectively above or below, or in front or in rear of one another, or of some reference point, is not intended to imply any limitation of my protection but is made simply for convenience of description, having regard to 25 the illustration of the invention in these drawings.

What I claim and desire to secure by Letters Patent is:

1. In a time piece, the combination, with 30 a hand driving member and an indicating hand, of an extension shaft which is constructed at one end to embrace part of said driving member and at the other end to mount said hand, that part of the shaft 35 which embraces said member and the part of the member embraced thereby, having interengaging offset portions formed and disposed to afford a driving clutch and to oppose yielding resistance to withdrawal of 40 the shaft from the driving member.

2. In a time piece, a rotatable hand driving member having a hub and said hub being formed with a notch in its outer side extending in a direction transverse to its 45 axis and in a line which cuts the path of rotation of said hub, an extension shaft having a hollow and split end formed and adapted to fit upon said hub and said split end having an offset portion complementary 50 to said notch arranged to enter the latter and to be held therein by the elasticity and resilience of the split portion of the shaft, said shaft having provisions at a part thereof distant from said driving member for 55 mounting an indicating hand, and a hand mounted thereon.

3. The combination of an indicator instrument having a dial and an enclosing case, a clock mounted outside of said case and hav-

ing a cannon pinion and an hour wheel coaxially arranged, each provided with a transverse notch in the side of its hub, intersecting the path of rotation thereof, an inner extension shaft fitting at one end detachably over said cannon pinion and having in its side an offset indentation engaging in said notch and resiliently held therein, a tubular outer extension shaft surrounding said inner shaft, fitting detachably over said hour wheel hub, and having in its side an offset indentation 70 engaging and resiliently held in the notch in said hub, said extension shafts both extending through the aforesaid case and dial, and time indicating hands mounted on said shafts over the face of said dial. 75

4. The combination of an indicator instrument with time indicating hands at the front, and a clock movement mounted at the rear thereof; a hand driving element constituting a part of said movement and having a hub, and an extension shaft carrying one of the hands and coupled to said hub, the hub and shaft being fitted one within the other and one of them having a protuberance and the other a depression receiving 80 said protuberance, the sides of said protuberance and depression being in engagement on lines transverse to both the length and the path of rotation of the shaft, thereby resisting independent movement of either 90 relatively to the other, the shaft being split at the end which engages the hub, whereby to permit yieldingly resisted displacement and replacement. 85

5. The combination of an indicator instrument having a dial, with time indicating hands rotatable over said dial, and a clock movement at the rear of the instrument, an hour wheel forming a part of the clock movement, an extension sleeve detachably 100 fitted to said hour wheel for rotational driving thereby and extending thence through said dial, the hour indicating hand being mounted upon the end of said sleeve and a minute hand driving member arranged coaxially within said hour wheel, an extension shaft fitted detachably upon said member for transmitting rotation therefrom and extending thence through said sleeve and carrying the minute indicating hand, said sleeve 105 having a bearing adjacent to that end thereof which is more remote from the clock movement, and the said shaft being rotatably held in said bearing. 110

In testimony whereof I have affixed my 115 signature.

GEORGE W. TONEY.
